(57) **CLAIM**

We claim the ornamental design for the monitor floating arm, as shown and described.

DESCRIPTION

FIG. 1 is a rear perspective view of a monitor floating arm showing the present invention;

FIG. 2 is a front view thereof;

FIG. 3 is a rear view thereof in;

FIG. 4 is a right side view thereof;

FIG. 5 is a left side view thereof;

FIG. 6 is a top view thereof;

FIG. 7 is a bottom view thereof;

FIG. 8 is a bottom perspective view thereof; and,

FIG. 9 is a top perspective view thereof.

The broken lines shown in FIGS. 1-8 illustrate portions of the monitor floating arm that form no part of the claimed design. The broken lines illustrating the monitor and table in FIG. 9 illustrate portions of the monitor floating arm that form no part of the claimed design.

1 Claim, 7 Drawing Sheets
